DESIGN FOR A TUMBLER

Jean Viatour, Soignies, Belgium, assignor to Libbey Glass Company, Toledo, Ohio, a corporation of Ohio

Application September 10, 1938, Serial No. 79,835

Term of patent 7 years

To all whom it may concern:

Be it known that I, Jean Viatour, a Belgian subject, residing at Soignies, in the Province of Hainaut, Belgium, have invented a new, original, and ornamental Design for a Tumbler, of which the following is a specification, reference being had to the accompanying drawing, forming a part thereof.

In the drawing:

Fig. 1 is a side elevational view of a tumbler showing my new design.

Fig. 2 is a top plan view thereof.

I claim:

The ornamental design for a tumbler, substantially as shown,

JEAN VIATOUR.
